UNITED STATES PATENT OFFICE.

HERBERT E. VAN DORN, OF CHICAGO, ILLINOIS.

DRAFT-RIGGING.

1,255,361.

Specification of Letters Patent.

Patented Feb. 5, 1918.

Application filed May 26, 1917. Serial No. 171,063.

To all whom it may concern:

Be it known that I, HERBERT E. VAN DORN, a citizen of the United States, residing at Chicago, county of Cook, State of Illinois, have invented a certain new and useful Improvement in Draft-Rigging, and declare the following to be a full, clear, and exact description of the same, such as will enable others skilled in the art to which it pertains to make and use the same, reference being had to the accompanying drawings, which form a part of this specification.

My invention has for its object to produce a simple, strong and durable draft rigging of the type wherein the coupler head is required to have a lateral and an up and down movement as well as a movement in the longitudinal direction.

A further object of my invention is to produce a simple and novel draft rigging which, upon the substitution of a simple element, is transformed from one in which the coupler is yieldingly supported for vertical movements to one in which there is no such yielding support.

A further object of my invention is to produce a simple and novel draft rigging in which the ordinary draw bar springs and springs for yieldingly supporting the coupler head for movements in the vertical direction are effectually housed and at the same time are easily accessible for inspection or removal and replacement.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a top plan view of a draft rigging arranged in accordance with a preferred form of my invention, detached from a car;

Fig. 2 is a side elevation of the parts shown in Fig. 1;

Fig. 3 is a central longitudinal vertical section, on an enlarged scale, through the middle portion of the rigging;

Fig. 4 is a section taken approximately on line 4—4 of Fig. 3;

Fig. 5 is a horizontal central longitudinal section through the parts shown in Fig. 3;

Fig. 6 is a section taken approximately on line 6—6 of Fig. 2; and

Fig. 7 is a view taken approximately in the plane of line 7—7 of Fig. 2, looking in the direction of the arrows.

Referring to the drawings, 1 represents a long strong casting connected at its rear end to a bracket, 2, adapted to be secured to the underside of a car frame, by means of a vertical pin, 3, whereby the member 1 is free to swing about a vertical axis. The front end of the member 1 is supported by a hanger, 4, adapted to be movably mounted on the usual curved supporting bar in the form of an arc of a circle having the pin 3 as its center. The front end of the member 1 is in the form of a box or housing, 5, the top and two sides of which are preferably integral with each other while the bottom is left open. The side walls of the housing are so shaped that they form front and rear stops, 6 and 7, for the follower plates, 8, of a spring cushion which, in the arrangement shown, consists of the usual helical springs, 9, lying between the two follower plates 8. The follower plates are embraced by a yoke, 10, extending above and underneath the same and attached at its front end to the shank or stem, 11, of a coupler. In the arrangement shown, the rear end of the member 11 is made in the form of a jaw into which the front end of the yoke extends. A heavy pivot pin, 12, extends horizontally through the rear end of the coupler shank and the front end of the yoke; this pin also extending through longitudinally elongated slots, 13, in the side walls of the draw bar box or housing, 5. On the outer ends of the member 12 are washers, 14, and, extending through the pin adjacent to the outer surface of the washer are keys, 15, which prevent the removal of the pin. With this arrangement, the coupler is adapted to move in and out against the tension of the springs and, at the same time, to swing up and down about the pin 12 as an axis.

On each side of the draw bar housing, in proximity to the front end thereof, are placed a pair of outwardly projecting ears, 16 and 17, the ear 17 of each pair lying behind and spaced apart from the other ear. The front end of the coupler is prevented from falling down by a suitable yoke device extending underneath the open front end of the housing and having its arms extending up between and attached to the ears 16 and 17. Where no considerable vertical play in the coupler head is desired, the yoke may be a

simple rigid supporting saddle. However, where it is desired to permit the coupler head to move up and down through a considerable distance, the yoke should contain a 5 vertically yieldable supporting seat. In the arrangement shown, the yoke comprises a spring box or housing adapted to lie underneath the main draw bar casting and having ears adapted to project up between and be 10 secured to the ears 16 and 17 on the opposite sides of the latter. The spring box is preferably divided along a horizontal plane into an upper member, 19, and a lower member, 20, the latter being closed at the bottom 15 and being secured to the member 19 by bolts, 21, or other suitable means. Within the spring box are springs, 22, resting at their lower ends in the bottom of the member 20. On top of the springs is a follower, 23, having a downwardly extending guiding flange or apron, 24, along its edge. The member 23 is provided at opposite sides with upwardly projecting ears, 25, between which extends a heavy pintle, 26, on which is supported a 25 saddle, 27, which is the direct means of support for the front end of the coupler. The front and rear walls of the member 19 are provided with openings or windows, 28 and 29, respectively, into which windows the 30 front and rear edges of the saddle 27 project. The lower edges, or what might be termed the sills of the windows or openings, serve as stops which limit the downward movement of the saddle. In view of the fact 35 that the downward movement of the coupler is a swinging movement and that therefore the saddle oscillates on the supporting pintle as it moves down, the lower edge of the window or opening, 28, is carried down below the plane of the lower edge of the window or opening, 29, so that the saddle, in its inclined position, will be engaged by both of its limiting stops without bringing any part of its upper surface out of engagement with 40 the overlying coupler shank.

In a sense, the spring cushion between the coupler and the draw bar is pivotally supported on the pin or shaft, 12, so that it will swing down out of the box or chamber 5 45 unless a support were provided for the rear end thereof. In order to support the spring cushion from below, I have provided a cover plate, 30, having upwardly projecting hooked portions, 31, along the side edges; 50 these hooked portions engaging with outwardly projecting flanges, 32, at the lower edges of the side walls of the housing 5. The cover plate is placed in position by sliding it lengthwise upon the flanges 32, these 55 flanges taking the load transmitted from the cover plate, so that dependence need not be placed upon bolts or other fastening devices for sustaining the load. The cover plate is 60 preferably held against accidental displacement by suitable bolts, 33, passing upwardly 65

through the same and through overlying parts of the draw bar housing. The cover plate is so shaped that the yoke 10 passes freely through the same while, at each side of the yoke-receiving spaces are ledges, as 70 indicated at 34, on which the follower plates rest.

While I have illustrated and described with particularity only a single preferred form of my invention, I do not desire to be 75 limited to the exact structural details thus illustrated and described; but intend to cover all forms and arrangements which come within the terms employed in the definitions of my invention constituting the appended 80 claims.

I claim:

1. In combination, a draw bar pivotally supported at its rear end for movements about a vertical axis, a coupler pivotally supported at the front end of the draw bar for movements about a horizontal axis, a spring cushion between the draw bar and the coupler for absorbing shocks in the longitudinal direction, a detachable yoke connected 90 to the front end of the draw bar and extending underneath the coupler, and a spring cushion arranged in said yoke and supporting the coupler from below.

2. In combination, a housing, a coupler 95 projecting into the front end of said housing, means for supporting the coupler so as to permit it to swing about a vertical axis, a cushion device between the rear end of the coupler and the housing, a yoke detachably 100 connected to the housing and underlying the coupler in advance of the pivotal axis of the latter, and a spring cushion arranged within the yoke underneath the coupler.

3. In combination, a supporting structure, 105 a coupler mounted upon said structure so as to permit the coupler head to move up and down, a spring box open at the top lying underneath the coupler and having arms extending upwardly beside the supporting 110 structure, a spring cushion in said box for supporting the coupler, and means detachably connecting said arms to said supporting structure.

4. In combination, a draw bar, a yoke lying 115 beneath said draw bar with its arms extending upwardly in proximity to the draw bar, means detachably connecting said arms to the draw bar, a spring cushion arranged within said yoke, a coupler extending 120 through said yoke and resting on said cushion, and means for connecting said coupler to said draw bar so as to permit the front end of the coupler to move in the vertical direction.

5. In combination, a draw bar having laterally projecting ears at the front end thereof, a yoke underlying the draw bar and having its arms extending upwardly and attached to said ears, a spring cushion 130

- arranged within said yoke, and a coupler resting on said spring cushion and attached to the draw bar so as to be movable vertically relatively thereto.
5. In combination, a draw bar, a yoke underlying the draw bar and having its arms projecting upwardly in proximity to the same, means attaching the said arms to the draw bar, vertically yieldable springs supported by said yoke between the arms thereof, a follower resting on said springs, a rocking saddle adapted to swing about a horizontal transverse axis supported by said follower, a coupler resting on said saddle, and 10 a pivotal connection between the coupler and the draw bar permitting the coupler to swing about an axis parallel with the aforesaid axis.
6. In combination, a housing, a coupler projecting into the front end of said housing, a spring cushion in the housing in rear of the coupler, a device extending between the rear end of the coupler and said cushion for transmitting draft and buffing strains thereto, a horizontal connecting pin extending through the rear end of the coupler and through said device, said housing having in its side walls opposed slots elongated in the longitudinal direction, and the ends of said pin projecting through said slots, and means for yieldably supporting the front end of the coupler against a downward swinging movement about said connecting pin.
7. In combination, a draw bar pivotally supported at its rear end for movements about a vertical axis and having at its front end a forwardly-opening chamber, a coupler extending into said chamber, a spring cushion arranged in said chamber between the rear end of the coupler and the draw bar, a detachable yoke connected to the front end of the draw bar and extending underneath the coupler, and a spring cushion arranged in said yoke and supporting the coupler from below.
8. In combination, a draw bar pivotally supported at its rear end for movements about a vertical axis and having at its front end a forwardly-opening chamber, a coupler extending into said chamber, a spring cushion arranged in said chamber between the rear end of the coupler and the draw bar,
9. In combination, a draw bar pivotally supported at its rear end for movements about a vertical axis and having at its front end a forwardly-opening chamber, a coupler extending into said chamber, a spring cushion arranged in said chamber between the rear end of the coupler and the draw bar,
- and means associated with the front end of the draw bar for yieldingly supporting the coupler so as to permit it to have a considerable vertical movement.
10. In combination, a draft member adapted to be supported to a car structure and having in the front end thereof a chamber open at the bottom and in front, a coupler 60 extending into said chamber, a spring cushion arranged within the chamber between the rear end of the coupler and the draft member for transmitting buffing and pulling strains from the coupler to the draft 65 member, and a yieldable support for the front end of the coupler extending across the open bottom of said chamber.
11. In combination, a housing open at the front end and on the under side, a coupler 70 projecting into the front end of said housing, a spring cushion arranged within the housing in rear of the coupler, a detachable bottom plate for supporting said spring cushion, a connection between said cushion 75 and said coupler for permitting the front end of the latter to move up and down, and a yieldable support carried by the front end of the housing for holding the coupler raised.
12. In a draft rigging, a spring box closed at the bottom and at the sides and open at the top, arms projecting upwardly from two opposite sides of said box, springs arranged within the box, a follower resting upon said springs, and a saddle pivotally supported on said follower for movements about a horizontal axis.
13. In a draft rigging, a spring box closed at the bottom and at the sides and open at 90 the top, arms projecting upwardly from two opposite sides of said box, springs arranged within the box, a follower resting upon said springs, a saddle pivotally supported on said follower for movements about a horizontal 95 axis, the front and rear sides of said box having windows therein, and said saddle having portions projecting into said windows and adapted to serve as stops to limit the downward movement of the saddle.
- 100 In testimony whereof, I sign this specification.

HERBERT E. VAN DORN.
